UNITED STATES PATENT OFFICE

157,680

GAME BOARD

John Harry Hill, Camden, N. J.

Application June 18, 1948, Serial No. 147,060

Term of patent 14 years

(Cl. D34—5)

To all whom it may concern:

Be it known that I, John Harry Hill, a citizen of the United States of America, residing at Camden, in the county of Camden and State of New Jersey, have invented a new, original and ornamental Design for a Game Board, of which the following is a specification, reference being had to the accompanying drawings, forming part thereof.

Fig. 1 is a plan view of a game board, showing my new design.

Fig. 2 is a sectional view taken as indicated by the lines and arrows II—II which appear in Fig. 1.

I claim:

The ornamental design for a game board, as shown.

JOHN HARRY HILL.
